UNITED STATES PATENT OFFICE

WILLIAM SPENCER BOWEN, OF WESTFIELD, NEW JERSEY

DESICCATING APPARATUS

Application filed May 8, 1928. Serial No. 276,017.

The invention relates to desiccating apparatus for the drying of liquids, semi-liquids, liquid emulsions, slurries, juices, syrups and other solid-containing liquids, and more particularly to a novel type of desiccating chamber which shall be self-cleaning inherently as well as in the provision of a shell or skin of a gaseous medium over its inner surface.

It has for its object a novel construction 10 of said chamber whereby the cooling action is inherent in the material of which the casing forming said chamber is composed, and develops automatically also more especially when a negative pressure is established with 15 in the chamber, for example, by connecting its outlet to suitable flow-inducing means which latter may serve to circulate the dried product and spent drying gases through said chamber. A further object of the invention 20 resides in the provision of means to prevent objectionable contact of the material treated with the wall of the treating chamber and in means for assisting in the removal of any particles of the product which may tend to de- 25 posit along the chamber wall.

In carrying out the invention, the novel casing is constructed throughout a portion of its length and, preferably throughout its entire length, of a foraminous material which, 30 also, is preferably flexible as of material such as fabric and the like. Material of this nature is useful also in assisting in the removal by evaporation from its external surface of any moisture tending to collect upon its in- 35 ner surface and soaking through to the outer surface. A further cooling action, it will be appreciated, results from this evaporation.

Moreover, to assist in maintaining the form 40 of this flexible casing material, which may be suspended from the top of a vertically dis- posed desiccating apparatus or stretched be- 45 tween supports, rings or like members are provided along its length about the same; and these are preferably flexibly attached, as by straps or tapes, to its outer surface so that 50 they may vibrate or swing against said cas- ing and through contact therewith assist in dislodging particles adhering to its inner sur- face and resulting from the desiccation of the solids in solution or suspension intro-

duced into said casing simultaneously with a gaseous drying medium.

The nature of the invention, however, will best be understood when described in connection with the accompanying drawings, in which:

Fig. 1 is a front elevation, partly in section, illustrating the novel desiccating apparatus; and Fig. 2 is a horizontal section there- 55 through, taken on the line 2-2, Fig. 1, and looking in the direction of the arrows.

Referring to the drawings, 10 designates a distributing casing, to be located at one end of the apparatus, for receiving the gaseous drying medium which may be supplied there- 60 to from a suitable source of supply (not shown) through a flue or duct 11. The said distributing casing is provided with a centrally disposed opening 12 through which the gaseous medium and a solid-containing liquid to be treated are introduced, said liquid, it 65 being understood, being provided in a finely divided state, in the particular embodiment shown being delivered through a suitable spray nozzle 13.

The solid-containing liquid and the gaseous drying medium thus simultaneously supplied are designed to flow concurrently through and to intermingle in a desiccating chamber formed by a casing 14 which, in accordance 70 with the invention, is to be composed of foraminous material over a portion and, preferably, substantially over its entire length.

Moreover, this material is also preferably of a flexible nature such as a suitable fabric, as canvas; and in this form may readily be suspended from the distributing casing 10. For example, it may be adjustably secured thereto, or rather to a ring member 15 ex- 75 tends downwardly therefrom by means of a clamping ring 16, the upper edge of the material being drawn upwardly the desired ex- tent to give the required tautness to the cas- ing whose lower edge is secured as, for exam- ple, about the outlet duct 17 which connects 80 with a flow inducing means such as the suc- tion fan 18. The lower end of the casing is 85 preferably constructed as frustro-conical; and, by thus attaching the opposite ends of said flexible casing to the respective rigid

supports 15 and 17, the casing may be properly extended, the tautness being determined as hereinbefore explained. At the lower end, said casing may be firmly secured as by means of a clamping ring 19 fitted over the inner end of the outlet duct 17.

The shape of the said casing may be further insured by surrounding the same with a succession of annular members as the rings 20 10 which are positioned along its length, more especially along its main cylindrical portion. If these rings be attached to the said casing, and particularly by flexible securing means as straps or tapes 21, as shown, said rings may 15 serve also as a means to assist in maintaining the inner wall of the casing free of particles of the desiccated material by vibrating or swinging during the desiccating operation against the outer surface of the casing and 20 dislodging thereby adhering particles.

The inner surface, however, is primarily kept free of such particles by constructing the casing of foraminous material, in which event air or other gaseous medium surrounding 25 the said casing will be drawn inwardly and in a substantially radial direction (as indicated by the arrows) through the openings 22 of said material and thus prevent particles from coming in contact with the said inner surface.

In addition, the entering gaseous medium, which may be at a reduced temperature, can thus serve also as a protective shell or skin over the inner wall to prevent particles of a 30 more or less sticky nature from adhering thereto as the temperature of the same will thereby be sufficiently lowered to overcome the tendency to become sticky at elevated temperatures such as may prevail in the gaseous drying medium.

The thickness of this skin or inner layer of gaseous medium will be determined, of course, by the degree to which the pressure within the casing is reduced below that of the atmosphere surrounding the casing and by 35 the area of the openings 22 therein. The suction fan 18 provides not only for this reduction of pressure within the chamber but secures the circulation of the sprayed liquid 40 and desiccating gases therethrough as well as their removal therefrom.

As hereinbefore noted, if the casing be composed of material such as a fabric, any moisture tending to collect upon its inner surface 45 will soak through to the outer surface to be evaporated therefrom and serving thus to enhance the cooling action of said casing. Moreover, there is no tendency of the casing to become clogged as it is really self-cleaning 50 in the action of the incoming jets of gaseous medium.

I claim:

1. Desiccating apparatus for solid-containing liquids, comprising a casing of foraminous material, means closing the upper end

of said casing, having an opening therethrough for the admission of the fluid to be desiccated and for a desiccating fluid medium, and flow-inducing means communicating with the opposite end of said casing for withdrawing spent gases therefrom and effecting thereby also radially directed jets of fluid medium from the surrounding atmosphere along the inner surface of said casing. 70

2. Desiccating apparatus for solid-containing liquids, comprising a desiccating casing of fabric substantially throughout its length, means to secure said casing at its upper end, closing the same thereat and having an opening therethrough for admission of the fluid to be desiccated and for a desiccating fluid medium, means to secure the fabric at its lower end to maintain said casing in a substantially vertical position, means to maintain substantially the shape of said casing intermediate its ends and embodying a plurality of ring members mounted about the same but displaced therefrom, and flow-inducing means communicating with the lower end of said casing for withdrawing spent gases therefrom and effecting thereby also radially directed jets of fluid medium from the surrounding atmosphere along the inner surface of said casing. 80

3. Desiccating apparatus for solid-containing liquids, comprising a distributing casing or head for a heated gaseous medium and having an opening therethrough, means to introduce through said opening solid-containing liquid, a desiccating casing of fabric hung from said distributing head to receive through its upper end the heated gaseous medium and the solid-containing liquid in finely-divided state, means to secure the lower end of the casing to maintain said casing substantially in a vertical position, means to maintain substantially the shape of said casing and embodying a plurality of ring members mounted about the same but displaced therefrom, and flow-inducing means communicating with the lower end of said casing to withdraw the spent desiccating medium through the said end and effecting thereby also radially directed jets of fluid medium from the surrounding atmosphere along the inner surface of said fabric. 90

In testimony whereof I affix my signature.
WILLIAM SPENCER BOWEN.
